PROCESS OF RENDERING OLEAGINOUS
TISSUE MATERIAL

Louis H. Libby, Boston, and Lloyd F. Henderson,
Reading, Mass., assignors to Lever Brothers
Company, Cambridge, Mass., a corporation of
Maine

No Drawing. Application April 26, 1945,
Serial No. 590,526

11 Claims. (Cl. 260—412.7)

1

This invention relates to the processing of oleaginous materials in order to recover oleaginous products therefrom, and more particularly to a process of rendering oleaginous tissue material to obtain fatty glyceride which have good color, and good stability against auto-oxidation and the development of odors and colors.

In general, rendering processes are conducted in either open vessels or closed vessels. The former may be open to the oxygen in the atmosphere and the latter may be protected therefrom. The processes also may be considered as of the wet type or of the dry type. In the wet type of rendering process, the rendering stock is heated or contacted with live steam. In the dry type of rendering process, the operation is carried out under conditions such that most of the moisture present in the stock being treated is removed. Many methods have been proposed heretofore for subsequently purifying, bleaching, or otherwise improving the products obtained by the usual rendering processes. These include treatment with various active reagents including acids, bases and salts. All of these refining or after-treatments have the economic drawback of adding to the cost of the process and leaving much to be desired in the final product.

Despite these numerous proposals, a large portion of commercial conventionally rendered tallow and other fats and oils is of poor color; they deteriorate rapidly into products of still poorer color and odor. It has been necessary for the users of fats to develop satisfactory processes for refining and bleaching lower grade stocks, or other processes of treating them so as to make them usable.

In sharp contrast to the heretofore known rendering processes and the resort to extensive bleaching of the rendered oils or fats to improve their color and other properties after rendering, it has now been discovered that rendered products having markedly improved color, odor, and stability against auto-oxidation may be obtained directly by an improved rendering process. More particularly the fatty tissue is rendered in the presence of a relatively small amount of a finely dispersed agent supplying hydrated silica to the mass being rendered, i. e., containing free hydrated silica or a material which yields it under the rendering conditions. Such agents are used

in a small amount and are relatively inexpensive; their use does not necessitate costly changes in rendering processes as usually practiced. Accordingly, the improved products are obtained at little or no additional cost. The improved products obtained in accordance with the invention are such as would command a higher market price than the unimproved fatty material; and also the need for subsequent bleaching thereof is either eliminated or reduced. They can be stored with less deterioration and used in the manufacture of higher grade soaps and other products.

It is an object of the present invention to provide an improved method for processing oleaginous materials.

It is another object of the invention to provide an economical and low cost process for rendering relatively low grade fat containing tissues or oleaginous materials to obtain relatively high grade oleaginous products such as glyceride fats and oils.

It is still another object of the invention to provide a process for rendering which may be carried out in the usual type rendering apparatus and following the established procedural techniques.

Other objects of the invention will be apparent as it is more fully disclosed hereinafter. These objects are achieved, in general, as follows:

30 In accordance with the invention, oleaginous stock or fatty tissue is rendered in the presence of silicic acid or any other agent containing or capable of furnishing hydrated silica to the mass and also capable of being finely dispersed therein.

35 Usually about 0.1% to about 5.0% of the added agents, based on the weight of the total mass, will suffice to give the improved product. For economic reasons the minimum amount is used which will give the desired improvement, considering the nature of the tissue to be rendered and the purpose for which the fat is to be used. The added agent is not dissolved in or carried over in the tallow or rendered oleaginous material product in appreciable amounts. For many purposes, the products obtained are directly usable.

The materials which may be added in accordance with the invention may be illustrated by hydrated silica, such as silicic acids or silica gel or hydrated amorphous silica or metasilicic acid. Other materials which comprise or supply hy-

hydrated silica include ethyl silicate, talc (a natural acid magnesium silicate), feldspar (a natural aluminum silicate rock which also usually contains at least one of the group potassium, sodium, calcium, barium, lithium and rubidium) and kaolin (a material resulting from the weathering of feldspar). Silica gel is a colloidal silicic acid or hydrated silica. All of these materials are characterized by their containing or being capable of furnishing hydrated silica in or to the mass being rendered under the rendering conditions. If the hydrated silica supplying agent has a saponifying action, it may be necessary to include an acidic material to suppress this action. Thus the process can be carried out under conditions in which there is no substantial saponification of oleaginous material or product.

In the standard rendering processes, the various grades of low grade stocks are generally treated separately and often treated differently. The primary tallow are prepared from suet trimmings, cord and kosher trimmings. Generally a yield of about 50% to 70% of the charge is obtained. Lower grade materials are obtained from inferior stocks such as bones, offal, and various scraps and waste fats from restaurants, household cooking grease, or from butcher shops. The yield of tallow from the bones and offal is about 20% of the weight of the charge. The oleaginous material which may be treated in accordance with the invention includes, among others, any of the foregoing types as well as vegetable and marine animal or fish types. In the recovery of fat from the latter types, the hydrated silica supplying agent may be added to the ground vegetable meats or marine animal meat in the cooking step, wherein the meats are conditioned for removal of the fat by a screw or hydraulic press or expeller. An improved fatty product will be obtained thereby.

The procedural operations do not vary from those employed in known rendering processes. For economic reasons the time of treatment and temperature used are generally the minimum required to remove the fat from the tissue. The fat may be removed at the end of the rendering or continuously, as is well known. The hydrated silica supplying agent may be mixed with the tissue before the heating is started if desired, or during the heating, and it may be added stepwise in one or more batches during the rendering.

Although the invention is not limited to any theory or explanation of the mode of operation or the results obtained, and no theory is claimed as such, it is thought that the following may be of aid in more fully understanding the invention.

The stocks to be rendered contain various color and color forming bodies. The presence of the hydrated silica agent is thought to prevent the dispersion of such bodies in the rendered fat. The stocks contain materials which are highly susceptible to auto-oxidation, and if these materials are carried into the fat, this property is also present in the rendered oleaginous product. The presence of the hydrated silica agent seems to destroy these bodies or prevent their removal with the fat and thereby prevents or represses auto-oxidation in the rendered material.

The following examples are given as illustrative but in no wise as limitations of the invention as otherwise disclosed herein. The materials of these examples were tested for deterioration by determining the amount of peroxides therein. They were tested for color in accordance with the

official methods of the American Oil Chemists Society using the standard Lovibond color glasses.

Example 1

5 A charge of beef trimmings was heated in an open vessel at 115° C. for 3/4 hours with agitation. The rendered fat was decanted from the residue tissue remaining in the vessel, and its color and peroxide number were determined.

10 Similar charges of similar trimmings were mixed with 1% (by weight) of a hydrated silica supplying agent, and heated at 115° C. for 3/4 hours in a similar vessel with agitation. The procedure was identical except for the presence of 15 the hydrated silica supplying agent in the mixture. The rendered fat was decanted and similarly tested for color and peroxide number.

The results of these tests follow:

20	Added agent	Rendered Fat			Peroxide No.	
		Color (8 1/4" Column)				
		Red	Yellow	Blue		
25	None.....	22.5	75	1.5	6.80	
	Feldspar.....	4.1	50	0	0.75	
	Talc.....	7.8	50	0	3.60	
	Amorphous Silica (Wet Ground).....	10.2	75	0	4.00	

30 These differences in color and peroxide number are striking, and the fat rendered in accordance with the invention is good for many purposes for which conventionally rendered fat could not be used except after earth bleaching. The cost of 35 the earth, the labor of bleaching, and the stock absorbed in the earth is all saved in accordance with the invention.

Example 2

40 (A) A charge of raw stock trimmings was heated in an open vessel to 125° C. with agitation for two hours. The rendered fat was decanted from the residual tissue or cracklings and tested for color, odor and peroxide number.

45 (B) The same procedure was followed except that the trimmings contained 1% (by weight) of metasilicic acid, i. e., they were heated with the metasilicic acid to a temperature of 125° C. for two hours with agitation. The rendered fat 50 was decanted and tested for color, odor and peroxide number.

The results of these tests follow:

55		A	B
		Color of Rendered Fat (8 1/4" column)	Peroxide No. of Rendered Fat after standing one day.
	Color of Rendered Fat (8 1/4" column)	4.0 Red, 50.0 Yellow.	0.9 Red, 9.0 Yellow.
	Peroxide No. of Rendered Fat after standing one day.	22.5.....	0.2.

60	Odor of Rendered Fat after standing over night.	A	B
	Poor.....	Good.	

These results clearly show a very marked improvement, obtainable by rendering in the presence of 1% of metasilicic acid.

Example 3

(A) In this example suet was used as the raw stock to be rendered and was heated at 130° C. 70 for one hour with agitation. The rendered fat was decanted and tested, as above.

(B) Suet containing 2% (by weight) of silica gel was heated at 130° C. for one hour with agitation, the procedure being the same as above 75 except for the presence of the silica gel in the

5 mixture. The rendered fat was decanted and tested, as above.

The results of these tests follow:

	A	B
Color of Rendered Fat (5 1/4" column). Peroxide No. of Rendered Fat after standing one day.	6.6 Red, 75.0 Yellow, 4.0 Blue. 42.9.	0.6 Red, 6.0 Yellow, 0.0 Blue. 16.98.
Odor of Rendered Fat after standing over night.	Poor.	Good.

In all of the above examples, the superiority, from the standpoint of color and deterioration, of the rendered fat obtained in accordance with the invention is readily apparent.

Example 4

(A) A mixture of equal weights of bone and suet was heated at 140° C. for 1 1/2 hours with agitation. The rendered fat was decanted from the residue tissue. Part of this product was tested for color, and another part was bleached with 6% (by weight) of activated earth and the bleached product tested for color.

(B) A similar mixture of equal weights of bone and suet but containing 1% (by weight) of metasilicic acid and 1% (by weight) of silica gel was heated at 140° C. for 1 1/2 hours with agitation. The rendered fat was decanted and a part of this tested for color, and another part bleached with 6.0% (by weight) of activated earth and the bleached product tested for color.

The results of these tests follow:

	A	B
Color of Rendered Fat (1" column). Color of Bleached Rendered Fat (1" column).	12.0 Red, 75.0 Yellow. 2.0 Red, 20.0 Yellow.	2.0 Red, 20.0 Yellow. 0.1 Red, 1.0 Yellow.

This example demonstrates the susceptibility of the tallow, rendered in accordance with the invention, to bleaching action. It would be difficult, if not impossible, to have bleached the ordinary rendered tallow to a color of 0.1 red and 1.0 yellow.

Example 5

(A) A sample of suet was rendered at 120° C. with agitation for one hour. The rendered fat was decanted. It tested 6.6 red in a 5 1/4" column. The fat was then treated with 2.0% (by weight) of silica gel at 120° C. for one hour with agitation in accordance with a standard procedure. The treated tallow was filtered. It tested 6.0

5 dered fat was decanted. It tested 0.6 red in a 5 1/4" column.

This example illustrates the marked difference between rendering in the presence of silica gel and the treatment of rendered fat with silica gel. It also shows that silica gel is not an efficient bleaching agent as compared with the known bleaching qualities of activated earths.

Example 6

10 A mixture of oleaginous rendering stock was made up of equal parts by weight of suet trimmings and cord flat. Equal parts of this mixture containing different hydrated silica supplying agents were heated at 125° C. with agitation for 1/2 hour. The rendered fat was decanted and tested for color and odor.

The results of these tests follow:

20	Added Agent	Color of Rendered Fat (5 1/4" Column)	Odor of Rendered Fat after Aging in Glass at 50° C. for One Month
25	None	6.0 Red, 75.0 Yellow.	Poor.
	1 weight percent ethyl silicate.	2.4 Red, 50.0 Yellow.	Excellent.
	1 weight percent metasilicic acid.	2.6 Red, 50.0 Yellow.	Good.
	0.5 weight percent metasilicic acid.	2.6 Red, 50.0 Yellow.	Do.

30 The data of this example show that even very small amounts of metasilicic acid may be used to advantage and also that an organic silicate such as ethyl silicate is a particularly efficient agent for use in accordance with the invention.

Example 7

35 Using a rendering stock similar to that of the preceding example, 10 lb. portions containing various added agents were heated at 120° C. with agitation for 70 minutes in an iron apparatus. The rendered fat was separated from the cracklings or residue tissue by filtering through a stainless steel screen. In some of the runs, a part of the rendered fat was tested for color, another part was converted to its soap, the soap bleached with 0.2 weight per cent of commercial sodium hydrosulfite and then converted into the free fatty acids; another part was bleached with a commercial activated earth. A part of this bleached tallow was tested for color, and another part thereof converted into its soap, washed and bleached with 0.2% sodium hydrosulfite and then converted into the free fatty acids. The free fatty acids were tested for color. The ethyl silicate and silica gel rendered products were tested for color only.

40 The results of these tests follow:

Added Agent	None	1 Weight Percent Metasilicic Acid	0.5 Weight Percent Metasilicic Acid	1.0 Weight Percent Silica Gel	1.0 Weight Percent Ethyl Silicate
Color of freshly Rendered Fat (5 1/4" Column).	15.5 R, 75.0 Y, 3.0 B.	4.7 R, 50.0 Y, 0.75 B.	5.8 R, 75.0 Y, 0.9 B.	6.0 R, 75.0 Y, 0.0 B.	5.4 R, 50.0 Y, 0.0 B.
Color of Fatty Acids from Soap from freshly Rendered Fat (5 1/4" column).	4.8 R, 50.0 Y	2.7 R, 27.0 Y	3.0 R, 35.0 Y		
Bleached Rendered Fats: Amount of bleaching agent used in weight percent.	6.0	3.0	4.0		
Color (5 1/4" column).	0.5 R, 5.0 Y	0.5 R, 6.0 Y	0.4 R, 4.0 Y		
Color of Fatty Acids from Bleached Rendered Fat (5 1/4" column).	2.5 R, 25.0 Y	1.2 R, 13.0 Y	1.5 R, 15.0 Y		

red in a 5 1/4" column, showing that the silica gel did not exert a bleaching action on the tallow.

(B) The same amount of suet in admixture with 2.0% (by weight) of silica gel was heated at 120° C. with agitation for one hour. The ren-

75 75 only about half of the bleaching agent required

for the fat from ordinary rendering processes. They also show that soaps made from such products yield lighter colored fatty acids.

Example 8

A rendering stock was made up of one part animal offal, 10 parts animal bone, two parts animal trimmings, and one part chicken offal.

(A) A charge of 50 lbs. of this stock was heated at 120° C. for two hours with agitation. The tallow was separated from the cracklings or residual tissue by straining through cheesecloth, settled overnight, and a portion thereof bleached with 6 weight per cent of activated earth at 105° C. for 15 minutes. A portion of the cracklings from each run was extracted with petroleum ether, the extract phase filtered through coarse filter paper, and the ether evaporated from the filtrate. The fresh tallow, bleached tallow, and oil from the cracklings were tested for color.

(B) A similar run and series of tests were made using 1 weight per cent of metasilicic acid in the rendering stock.

The results of these tests follow:

	A	B
Color of freshly Rendered Fat (5 $\frac{1}{4}$ " column). (1" column)	86.5 R, 75.0 Y, 3.0 B. 10.0 R, 75.0 Y.	37.5 R, 75.0 Y, 1.45 B. 4.7 R, 50.0 Y.
Color of bleached Rendered Fat (5 $\frac{1}{4}$ " column).	8.0 R, 50.0 Y.	3.5 R, 35.0 Y.
Color of oil from cracklings (1" column).	16.5 R, 75.0 Y.	6.0 R, 75.0 Y.

These data show that the presence of a hydrated silica supplying agent in even low grade rendering stocks gives a very much improved product and that bleached products obtained therefrom are much better than those from ordinary rendering processes. They also indicate that the agent acts to set or destroy the color in the residue, so that it is not carried over into fat or oil extracted therefrom by solvent extraction processes. This is a very important economic advantage of the new process.

It is appreciated that it has been proposed heretofore to render fat in the presence of activated carbon by methods which protect the stock from oxygen of the atmosphere when it is at the high temperatures used in rendering. The hydrated silica supplying substances used in accordance with the invention are not the equivalents of activated carbon, since the hydrated silica supplying substances are efficient in rendering in the presence of air. This is a marked advantage in a commercial operation.

By "rendering" is meant heating to a temperature above room temperature which facilitates the removal of the oil or fat from the tissue while maintained at said temperature, or in a later removing operation which may or may not be carried out at said temperature and which may or may not include mechanical expression of the oil or fat from the tissue.

In view of the foregoing disclosures, it will be apparent to one skilled in the art that this process may be applied to stocks equivalent to those mentioned, using equivalent hydrated silica supplying agents, in accordance with the invention. The invention contemplates all modifications within the scope of the appended claims.

We claim:

1. A method which comprises rendering oleag-

nous tissue material by heating it to a temperature which facilitates removal of fatty glyceride therefrom, in the presence of a small proportion of a substance supplying finely dispersed hydrated silica thereto, and separating the rendered fatty glyceride therefrom.

2. A method which comprises rendering oleaginous tissue material by heating it to a temperature which facilitates removal of fatty glyceride therefrom, in the presence of oxygen and a small proportion of a substance supplying finely dispersed hydrated silica thereto, and separating the rendered fatty glyceride therefrom.

3. A method which comprises rendering oleaginous tissue material by heating it to a temperature which facilitates removal of fatty glyceride therefrom, in the presence of a small proportion of a finely dispersed hydrated silica containing substance, and separating the rendered fatty glyceride therefrom.

4. A method which comprises rendering oleaginous tissue material by heating it to a temperature which facilitates removal of fatty glyceride therefrom, in the presence of a small proportion of a finely dispersed hydrated silica, and separating the rendered fatty glyceride therefrom.

5. A method which comprises rendering oleaginous tissue material by heating it to a temperature which facilitates removal of fatty glyceride therefrom, in the presence of a small proportion of a finely dispersed talc, and separating the rendered fatty glyceride therefrom.

6. A method which comprises rendering oleaginous tissue material by heating it to a temperature which facilitates removal of fatty glyceride therefrom, in the presence of a small proportion of a finely dispersed feldspar, and separating the rendered fatty glyceride therefrom.

7. A method which comprises mixing oleaginous tissue material with about 0.1% to about 5.0% of a substance supplying finely dispersed hydrated silica thereto, based on the weight of the total mass, rendering the tissue by heating to a temperature which facilitates removal of fatty glyceride therefrom, and separating the rendered fatty glyceride therefrom.

8. A method which comprises mixing oleaginous tissue material with about 0.1% to about 5.0% of a finely dispersed hydrated silica containing substance, based on the weight of the total mass, rendering the tissue by heating to a temperature which facilitates removal of fatty glyceride therefrom, and separating the rendered fatty glyceride therefrom.

9. A method which comprises mixing oleaginous tissue material with about 0.1% to about 5.0% of a finely dispersed hydrated silica, based on the weight of the total mass, rendering the tissue by heating to a temperature which facilitates removal of fatty glyceride therefrom, and separating the rendered fatty glyceride therefrom.

10. A method which comprises mixing oleaginous tissue material with about 0.1% to about 5.0% of a finely dispersed talc, based on the weight of the total mass, rendering the tissue by heating to a temperature which facilitates removal of fatty glyceride therefrom, and separating the rendered fatty glyceride therefrom.

11. A method which comprises mixing oleaginous tissue material with about 0.1% to about 5.0% of a finely dispersed feldspar, based on the weight of the total mass, rendering the tissue by heating to a temperature which facilitates re-

moval of fatty glyceride therefrom, and separating the rendered fatty glyceride therefrom.
